UNITED STATES PATENT OFFICE.

JOSEPH CHMIELINSKI, OF PASSAIC, NEW JERSEY.

FOUNTAIN-BRUSH.

1,351,371.

Specification of Letters Patent. Patented Aug. 31, 1920.

Application filed February 11, 1919. Serial No. 276,258.

To all whom it may concern:

Be it known that I, JOSEPH CHMIELINSKI, a citizen of the United States, residing at Passaic, in the county of Passaic and State 5 of New Jersey, have invented certain new and useful Improvements in Fountain-Brushes; and I do hereby declare the following to be a full, clear, and exact description of the invention, such as will enable 10 others skilled in the art to which it appertains to make and use the same.

This invention relates to brushes and the primary object of the invention is to provide an improved brush in which a quantity 15 of material to be applied to a surface is carried by the brush so as to obviate the necessity of dipping the same into a receptacle containing the material.

Another object of the invention is to provide an improved fountain brush in which the parts thereof are so arranged, with relation 20 to each other, that the brush can be readily disassembled whereby the various parts can be quickly and thoroughly 25 cleaned.

A still further object of the invention is to provide an improved fountain brush of the above character, which is durable and efficient in use, one that is simple and easy 30 to manufacture, and one that can be placed upon the market at a reasonable cost.

With these and other objects in view, the invention consists in the novel construction, arrangement and formation of parts, as will 35 be hereinafter more specifically described, claimed and illustrated in the accompanying drawings, forming a part thereof, in which:

Figure 1 is a longitudinal vertical section 40 through a brush constructed in accordance with this invention.

Fig. 2 is a horizontal section taken on the line 2—2 of Fig. 1.

Referring to the drawings, in detail, 45 wherein similar reference characters designate corresponding parts throughout the several views, the numeral 1 generally indicates the brush which includes a tubular body 2 gradually tapered toward the upper 50 end thereof, which is provided with external screw threads 3 on which is fitted a removable cap 4, which forms means whereby the liquid may be placed in the same.

The lower or flared end of the body 2 is 55 provided with internal screw threads 5 in

which is fitted the head 6 of a brush 5. By threading the brush head, it can be seen that the brush can be readily removed so that the same can be easily cleaned, or another brush substituted therefor when the 60 original one has become worn or when a different colored paint is to be used.

A funnel-shaped member 7 having the lower reduced end 8 thereof extended into the brush head which is provided with a 65 central aperture 9 for receiving the same.

A butterfly valve 10 is provided for controlling the flow of liquid from the hollow body 2 to the funnel member 7 and thus to the brush 5. The butterfly valve 10 is provided 70 at opposite diametrical points with inwardly extending threaded apertures 11, in which is adapted to be fitted pivot pins 12, which are rotatably received in apertures 13 formed in the body 2 at opposite diametrical points. One of the pins 12 is provided 75 with a thumb piece 13, whereby the valve may be readily turned. By threading the pins 12 into the valve 10, it can be seen that the pins can be readily removed from the 80 valve and thus allow the same to be removed, so as to allow the valve to be cleaned and scraped and the tubular body.

The funnel-shaped member 7 is provided with a downwardly extending annular 85 flange 14, which is adapted to rest upon the brush head 5 and forms means for holding the funnel-shaped member in correct position.

From the foregoing description it can be 90 seen that an improved fountain brush is provided, in which the parts thereof can be readily disassembled, so as to permit the same to be readily cleaned.

In practice, I have found that the form 95 of my invention illustrated in the accompanying drawings and referred to in the above description, as the preferred embodiment, is the most efficient and practical; yet realizing the conditions concurrent with the 100 adoption of my device will necessarily vary, I desire to emphasize that various minor changes in details of construction, proportion and arrangement of parts may be resorted to, when required without sacrificing 105 any of the advantages of my invention as set forth.

What I claim as new is:

A fountain brush comprising a hollow body having each end open, a brush thread- 110

ed in one end of said body, a funnel shaped member disposed in the body and having its neck portion positioned in the brush, an annular supporting flange formed on the 5 enlarged end of the funnel shaped member and resting on the brush and against the wall of said body to hold the neck portion within said brush, a valve in said body adjacent the funnel shaped member and adapt-

ed to control liquid thereto, and a removable closure for the other end of said body.

In testimony whereof I affix my signature in presence of two witnesses.

JOSEPH CHMIELINSKI.

Witnesses:

JOSEPH PARTKIEWICZ,
STANLEY KWAPICK.
